SMOKER'S PIPE

Ben Lieber, Brooklyn, N. Y., assignor to Aply-Tec Products, Inc., Brooklyn, N. Y., a corporation of New York

Application April 20, 1955, Serial No. 35,592

Term of patent 14 years

(Cl. D85—8)

Fig. 1.

Fig. 2.

Fig. 3.

Fig. 4.

Fig. 1 is a perspective view of a smoker's pipe embodying my new design;

Fig. 2 is a top plan view of said pipe;

Fig. 3 is a side elevational view of said pipe; and

Fig. 4 is a section of said pipe taken on the line 4—4 of Fig. 3.

I claim:

The ornamental design for a smoker's pipe, substantially as shown.
